SHEET LENGTH INDICATOR FOR CUTOFF KNIVES

Thomas S. Fitchett, Glenarm, Md., assignor to
 F. X. Hooper Company, Inc., Glenarm, Md., a
 corporation of Maryland

Application November 25, 1943, Serial No. 511,716

10 Claims. (Cl. 164—63)

The invention relates to a cut-off knife for corrugated board and similar box material, the same being adapted to the cutting of a moving web, forming sheets or blanks, mainly for use in the manufacture of knock down boxes. The machine shown is of the rotary type to which the paper web is fed at a constant speed, the speed of the knife being controlled and changed to give the number of cycles or cuts per unit of time essential to the desired length of the blanks or sheets, and also in the most approved form to change the speed of the cutters within each cycle at the time of cutting to conform the speed of the cutters to the speed of the paper.

In the rotary type of machine shown and in other machines for the same purpose, the web passes freely by the cutting blades or knives at all times, except when they are in cutting engagement with the web, the gearing which drives the cutters being of types well-known in the art which give the desired change within each cycle, for conforming the speed of the cutters to the speed of the paper, giving a smooth even cut. This gearing or mechanism is in turn driven by a change speed gear which is adjustable to determine the length of the sheet to be cut by regulating the number of cycles of the cutter motion for unit of time, the speed of the web as aforesaid being constant.

For this latter purpose, well-known change speed units are usable as the Reeves drive or a similar but more positive device known as P. I. V. and usually described as positive and infinitely variable or positive, infinite, variable, made by Link Belt Co., other makes being presumably available.

In both types, the speed changing elements include a belt of tapering cross-section, connecting driven elements, each of which elements consists of a pair of correspondingly tapered pulleys, the pulleys of each pair being moved oppositely, in axial directions, each toward and away from the other, changing oppositely the effective radius of the driving and driven pulleys.

These changes of speed are effected by an adjusting screw which controls the spacing of the respective pairs of pulleys, and is operable from outside of the change speed gear casing, but it has been ascertained, that, at least with the pulleys and belts now embodied in the change speed gear, the change of speed is not proportionate to the angle of rotation of the screw which thus changes the effective radius of the pulleys.

While this variation can be computed and a corresponding dial can be made, such a dial would be of inconveniently large size and the graduations of varying lengths so that such indicators are difficult for the average operator of these machines to use correctly.

The purpose of the invention is to provide an 60 the machine.

index which will function in cooperation with the cut-off knife, as suggested above, and which is of satisfactory size, shape, and proportions, and is so easily readable, as to enable the average operator in a paper box plant to set the machine instantaneously, changing the length of sheets while running from one standard length to another, with the minimum chance of error and hence the minimum waste of material. A condition that must be met is that the required change of the position of the pointers on the indicator dial which is necessary to make the desired change of sheet length, must be obvious to the degree of intellect possessed by the average operator. The changes must be almost instantaneous and made while the machine is running.

According to the regular practice in the manufacture of corrugated paper boxes, the blanks vary in length by differences of one inch or fraction thereof from a minimum of twenty-five inches to a maximum of one hundred and eighty inches. There must therefore be approximately 155 one-inch graduations as suitable sub-divisions on the dial. It has been found most effective in obtaining the highest degree of efficiency and economy of operation of the machine to have all the graduations spaced well apart, and to have the spaces uniform, and further it has been discovered that a spacing of the marks or graduations directly corresponding to the differences between successive sheet lengths in the series being followed is most effective in avoiding errors in setting. At the speed of the present machines, such errors, if discovered immediately, are expensive in the resulting waste of corrugated paper or other material, and if not detected immediately, involve extensive losses in each instance.

The device of the invention as shown, has graduations spaced by uniform 1 inch intervals, i. e. equal to the differences in sheet lengths, and arranged in a helical line on a small rotatively mounted cylinder which is connected by a reducing gear, to a screw which moves a pointer over the surface of the cylinder, and the cylinder is connected to the change speed adjusting screw by a compensating device, whereby the rotation of the adjusting screw from the minimum length to the maximum length cutting positions moves the pointer in parallelism with the axis, and rotates the dial, causing the pointer to pass over the surface of the cylindrical dial on a substantially helical line, which in the present instance is the line of said graduations, 155 inches long, in the preferred form and divided into equal spaces, each division being in said preferred form, suitably marked with the total lengths in inches of the corresponding sheets, each space representing accurately a corresponding change in the length of sheet being cut by

The drawings show as an example of the compensating device, a one flight belt or otherwise a butt ended belt or cable, wound at one end on a spiral pulley, the path of which has a change of radius corresponding to the required compensation, said pulley being on or directly driven by the change speed adjusting screw shaft, the other end of the cable being wound on a cylindrical or other suitable pulley, affording a helical path for the cable. The latter pulley is shown as integral with the dial cylinder, various changes of this arrangement giving the same result being contemplated.

In the drawings,

Figure 1 is a diagrammatic view, showing the relation of the parts in the combination which is the subject of the invention.

Figure 2 is a side elevation of the dial cylinder and correlated parts.

Figure 3 is a perspective view of the cut-off machine with the sheet length blank indicator and control in its operative relation thereto.

Referring to the drawings by numerals, each of which is used to indicate the same or similar parts in the different figures, and having particular reference to Figure 1; the cutter cylinders 1 and 2 for which other suitable mounting of the cutters may be substituted are driven by gearing 3, contained within the casing 4 of which the disclosure of Patent No. 2,052,461, of August 25, 1936, is an example, other drives being usable.

In the form shown, the cutter drive or gearing 3 is driven from a pinion 5, secured to a shaft 6 which is in turn driven by a Reeves drive or other similar type of change speed of which the P. I. V. is a good example, the drawings being treated as showing either form of change speed gear. Such gearing as already pointed out consists of two pairs of opposed frustoconical pulleys 7 and 8, mounted on parallel shafts 6 and 9 with which shafts the pulleys are engaged in driving relation, being however, slidably longitudinally of the shafts.

The change speed gear illustrated which is found satisfactory shows two shifting levers 11 and 12, pivotally mounted intermediately of the length of each at 14 on a suitable support which is stationary in the casing 15. Each of these levers is connected to corresponding pulleys of the respective pairs 7 and 8, and their ends which project beyond the pair of pulleys 8 are engaged respectively by a right and left hand threaded screw 16, whereby the rotation of the screw causes the pulleys of the respective pairs, to be moved simultaneously and oppositely, one toward or away from the other, for purposes more fully hereinafter discussed.

In the form shown, the shaft 9, which may be regarded as driving the machine through the change speed gearing contained in casing 15, carries secured thereto a large pulley 17 outside the machine casing and the machine is customarily driven from the usual power shaft by a belt running on said pulley. The corrugator or other machine which supplies the web to the machine just described which is referred to as a cut-off knife 20, is connected in any suitable manner as by bevel gears 18, to driving shaft 19 which drives the corrugator or equivalent machine delivering a paper web to the cut-off knife 20 in predetermined positive relation to the speed of shaft 9.

The adjusting screw 16 as shown, is mounted in suitable bearings 16' in the change speed gear casing 15, and may if desired be operated by a

hand crank or the like. In the form shown, it is rotated for the purpose of changing the speed of shaft 6 by means of a motor 21, the shaft 22 of which is threaded in the form of a worm which engages and drives a worm gear 24 on and in driving relation to a transverse shaft 25 parallel to the screw 16. This shaft carries a sprocket 26 which drives a sprocket chain 27 which in turn engages a sprocket 28 on the adjusting screw shaft 16, and drives the latter.

This shaft 16 carries secured thereto a pinion 30 which meshes with and drives a relatively large gear 31 shown as an internal gear which as illustrated rotates on a shaft 32, parallel to the screw 16. This internal gear 31, the exact form being immaterial, is shown as secured to a spiral pulley 33.

This spiral pulley 33 in the form of the invention shown operates a cable 34 and the spiral pulley 33 is provided with a path 35 for said cable, said path being of increasing radius from one axial end of said pulley toward the other.

In the form shown, the cable 34 is attached at one end to the small radius or short radius end of the pulley 33 and thus winds up on the pulley, the take-up of the cable by the pulley increasing in proportion to the rotation of the pulley, and hence of the adjusting screw 16, as the tangent point or take-off point of the cable at 34' in the position shown approaches the large end of the pulley.

In other words, and more particularly, the radius of the pulley 33, and hence the take-up of the cable 34 increases in proportion to the decrease of the speed of the shaft 6 as compared to the rotation of adjusting screw 16 from the position of the parts shown which is the position for cutting the minimum length sheets, herein designated as 25 inches. In other words, in the position shown, the cutter cylinders 1 and 2 are operated at a relatively high speed, as compared to the speed of the web, which is dependent on the speed of shaft 9 which is constant. The speed of shaft 6 and the number of cycles per unit of time decreases as the screw 16 is turned from the limiting position shown, thus increasing the length of the blanks cut. The pulley 33 and the other parts of the change speed mechanism above described are drawn in proportion and to scale from the blueprints from which applicant's machine was made. Successive points on the pulley 33 are calculated according to well-known mechanical principles to correspond to successive positions of the belt on the pulleys 7 and 8. The principles of mathematics and mechanics involved are familiar to designers of machinery and not part of the invention.

In the form shown, the cable 34 is passed around an idler or guide pulley 36 and has its other end wound in a predetermined path 37 about what is preferably a cylindrical pulley 38 connected or secured to the dial cylinder 39. The cable rotates the cylinder in one direction as said cable is rolled up in the spiral pulley 33, and a coil spring 39' keeps the cable under tension and turns the cylinder in the opposite direction.

This cylinder 39 is secured to a shaft 40, mounted in suitable stationary bearings 41, on a support 42, mounted on the machine frame.

In the form shown, a gear 43 is secured to the cylinder 39, the same being, conveniently, about the size of the cylinder and a lead screw 44, mounted in suitable bearings and turning on an axis parallel to the axis of the dial cylinder has

secured thereto a pinion 45, meshing with the gear 43.

The screw 44, carries a pointer 46, having a suitably apertured end 47 which moves relatively to the cylinder on a path which is the result of the combination of the pitch of the screw and the relation to each other of gears 43 and 45. This path if traced on the cylinder would be in the nature of a helix.

According to the existing practice in this art, the sheets or blanks vary by differences of one inch or fraction thereof from a minimum which is usually 25 inches to a maximum of 180 inches, and the helical path 48 is graduated in an approximately equal and preferably in precisely 15 equal spaces marked according to the corresponding sheet or blank lengths from 25 to 180, and preferably an inch in length with suitable subdivisions.

The use of one inch graduations numbered according to sheet length or similar uniform graduations, is found to be of distinct advantage in teaching the average operator, as compared to graduations of varying length for the same purpose and it is also found that in this way, numerous expensive mistakes in setting the machine are avoided.

The fact that the compensating device 33, 34, etc., makes a considerable saving in the size of the dial will be apparent from the fact that it equalizes the length of the graduations and without it, the short graduations being of reasonable and satisfactory length, those which are necessarily longer would be of comparatively great length, requiring a dial of excessive size which is in fact an existing known difficulty in this art.

The cylindrical dial 39, having the graduations arranged in a helical path thereon also effects a considerable saving in the overall size of the dial. While a circular dial may be used with a pointer operated by the spiral pulley 33, the dial being marked with one inch or other suitable graduations, and such use is regarded as within the broader scope of the invention, it is a simple matter of mathematics to ascertain that, with the convenient one inch graduations, such a dial would be about 4 feet in diameter and without the compensating device as the spiral pulley 33, and using a circular dial, if the minimum graduations are of a length of one inch, the maximum length of graduation would be considerably longer, whereby the circular dial would be 6 or 8 feet in diameter, a size which would be wholly unsatisfactory and out of proportion to the size of the machine, and the variation in the length of the graduation would result in numerous expensive mistakes in the nature of incorrect setting of the machine, it being borne in mind that the average operator on said machine is not a mathematician or a scientist and not very alert after spending hours in succession in attending the machine.

In Fig. 3 the motor 55 is for operating an adjustment to change of speed of the knife in its cutting cycle to conform to the speed of the paper. The switch 56 is for controlling the motor 55 to determine said adjustment. This is no part of the present invention.

The switches 49, 50, 51 are in circuit with the motor 21 for operating the same forwardly and in reverse, 52 being a cable containing the wiring for said switches. This cable 52 is also indicated in Fig. 1 which is diagrammatic. In the latter figure 54 is a battery or other source of electricity for operating the motor 21. Such wiring being 75

familiar, no wiring diagram is deemed necessary.

In Fig. 3 one cut-off knife blade is shown at 57 on cylinder 2; the corresponding knife being shown on the cylinder 1 at 57' in Fig. 1.

In considering the operation of the apparatus, it may be noted, it is customary to set the machine while running, and that in so doing, the operator starts the motor 21, in the proper direction, turning the adjusting screw 16, and hence moving the dial 39, and the pointers until the desired operating position is reached, which is almost instantaneously. In view of the speed with which this change is made, the importance of the equal length graduations corresponding to the changes of sheet length will be apparent. As soon as the proper number of graduations has been passed, and the number corresponding to the desired sheet length appears at the end of the pointer 46, the motor is stopped and if the precise adjustment has not been reached, it may be further operated, forwardly or in reverse. A quick and accurate adjustment is important, as during the change, the web and the cut-off knife are running, cutting sheets of varying length which are not usable in the manufacture of boxes or the purposes to which the cut-off sheet may be put.

A sheet length control and an indicator therefore, as an example of a satisfactory embodiment of the invention, having been thus described. It will be understood that changes within the skill of the average mechanic acquainted with this art are contemplated.

35 What I claim as new and desire to secure by Letters Patent is:

1. The combination with a cut-off knife for making transverse cuts whereby sheets of predetermined, uniformly varying series of lengths are cut from a web, moving at a constant speed in cutting relation to the knife, said machine having means for moving the knife in successive cutting cycles and a change speed gear for driving said moving means to operate the knife in said cycles and a rotatable adjusting shaft for controlling said change speed gear to change the number of cycles per unit of time, the rotation of said shaft having a predetermined variation relatively to the extent of said changes of speed, of a cylindrical dial having index marks arranged in a helical line and numbered progressively in correspondence with said series of blank lengths, a driving connection from said adjusting shaft to said cylinder, a pointer with means 40 for moving the same along the cylinder in an axial direction in correspondence with the rotation of the cylinder, whereby the pointer follows said line, said connection from the adjusting shaft to the cylinder, including a compensating 45 device corresponding to said determinable variation, whereby the cylinder rotates in direct correspondence to the changes of the number of cycles per unit of time.

2. The combination as in claim 1, in which the spacing of the index marks is equal to the differences between the successive blank lengths in said series.

3. The combination with a cut-off knife for making transverse cuts, whereby sheets of predetermined lengths, comprising a series of uniformly varying lengths, are cut from a web, moving at a constant speed in cutting relation to the knife, said machine having means for moving the knife in successive cutting cycles and

a. change speed gear for driving said means to operate the knife in said cycles and a rotatable adjusting shaft for controlling said change speed to change the number of cycles per unit of time, the rotation of said shaft having a determinable variation, relatively to the extent of successive changes of speed, of a cylindrical dial having index marks arranged substantially in a helical path and numbered progressively in correspondence with said series of blank lengths, a pointer with connections to said shaft for moving the pointer along said line in correspondence with the changes of sheet lengths, said connection from the adjusting shaft to the pointer, including a compensating device corresponding to and adapted to compensate for said determinable variation, whereby the pointer moves in direct correspondence to the changes of the number of cycles per unit of time, and hence with said changes of sheet lengths.

4. The combination with a cut-off knife for making transverse cuts, whereby sheets of predetermined lengths comprising a series of suitably varying lengths, are cut from a web moving at a constant speed in cutting relation to the knife, said machine having means for moving the knife in successive cutting cycles, and a change speed gear for driving said means to operate the knife in said cycles and a rotatable adjusting shaft for controlling said change speed to change the number of cycles per unit of time, the rotation of said shaft having a determinable variation relatively to the extent of successive changes of speed, of a dial having index marks arranged in a line and numbered progressively in correspondence with said series of blank lengths, a pointer with connections to said shaft for moving the pointer along said line in correspondence with the changes of sheet lengths, said connection from the adjusting shaft to the pointer including a compensating device in the form of a spiral pulley and a tension member wound thereon, the diameter of the pulley being varied in correspondence with said determinable variation whereby the pointer moves in direct correspondence to the changes of the number of cycles per unit of time and hence with said changes of sheet lengths.

5. The combination with a cut-off knife for making transverse cuts, whereby sheets of predetermined variable lengths are cut from a web moving at a constant speed in cutting relation to the knife, said machine having means for moving the knife in successive cutting cycles, a change speed gear for driving said means to operate the knife in said cycles and a rotatable adjusting shaft for controlling said change speed gear to change the number of cycles per unit of time, of a cylindrical dial having index marks arranged in a helical line and numbered progressively in correspondence with a series of blank lengths to be cut and spaced each from the next by an interval, a driving connection from said shaft to said cylinder, a pointer with connections for moving the same along the cylinder in an axial direction, in correspondence with the rotation of the cylinder, whereby the pointer follows said line.

6. The combination as per claim 5 in which the changes of speed have a definite variation, relatively to the extent of rotation of the adjusting shaft and said connections from the adjusting shaft to the cylinder include a compensating device arranged in correspondence with said definite variation, whereby the cylinder

rotates in direct proportion to the changes of the number of cycles per unit of time.

7. The combination as per claim 5, in which the changes of speed have a definite variation, relatively to the extent of rotation of the adjusting shaft and said connections from the adjusting shaft to the cylinder include a spiral pulley of a radius varying in correspondence with said definite variation, and a tension member wound thereon and driving said cylinder, whereby the cylinder turns in direct proportion to the changes of the number of cycles per unit of time.

8. The combination with a cut-off knife for making transverse cuts, whereby sheets of predetermined lengths comprising a series of suitably varying lengths are cut from a web moving at a constant speed in cutting relation to the knife, said machine having means for moving the knife in successive cutting cycles, a change speed gear for driving said means to operate the knife in said cycles, and a rotatable adjusting screw shaft for controlling said change speed to change the number of cycles per unit of time, the rotation of said shaft having a determinable variation relatively to the extent of successive changes of speed, of a dial movably mounted and having index marks arranged in a line and numbered progressively in correspondence with said series of blank lengths, a pointer also movably mounted with connections to said shaft for moving the pointer in correspondence with the changes of sheet lengths, said connection from the adjusting shaft to the pointer including a compensating device corresponding to and adapted to compensate for said determinable variation, the dial also being operatively connected through the compensating device to the adjusting screw shaft whereby the reading is the resultant of the dial motion combined with the pointer motion.

9. The combination as per claim 5 in which both differences between successive sheet lengths and the intervals on the dial are one inch in length and the index marks are designated according to corresponding sheet lengths.

10. The combination with a cut-off knife for making transverse cuts, whereby blanks of predetermined uniformly varying lengths are cut from a web moving at a constant speed in cutting relation to the knife, said machine having means for moving the knife in successive cutting cycles, a substantially constant source of power, a change speed gear connected to said source and having a driving connection to said moving means to operate the knife in said cycles and control means operatively connected to said change speed gear to change the number of cycles per unit of time changing the blank lengths, the movement of said control means having a predetermined variation relatively to the extent of said changes of speed; blank length indicating means including a dial having spaced index marks numbered progressively in correspondence with said blank lengths and a pointer, a driving connection from said control to both the dial and pointer of said length indicating means both of which are movably mounted, whereby the indicating means is operated to designate indicator marks corresponding to the length of blanks being cut, said driving connection from the control to said length indicating means, including a compensating device, operating in correspondence to said predetermined variations to cause the indicating means to move in direct correspondence to the change of sheet lengths.
